UNITED STATES PATENT OFFICE.

JEAN SZYKIER, OF BERLIN, GERMANY, ASSIGNOR TO SEMPLUX G. M. B. H., OF BERLIN, GERMANY.

MAGAZINE FUSE PLUG.

Application filed June 3, 1921. Serial No. 474,727.

To all whom it may concern:

Be it known that I, JEAN SZYKIER, a citizen of the Russian Republic, residing at Berlin, in the German Empire, have invented 5 new and useful Improvements in Magazine Fuse Plugs, of which the following is a specification.

My invention relates to improvements in magazine fuse plugs, and the objects of the 10 improvements are to provide a fuse plug of this class which is strong in construction, and in which insertion of a wrong fuse is made impossible. With these and other objects in view my invention consists in the 15 matters to be described hereinafter and particularly pointed out in the appended claims.

For the purpose of explaining the invention several examples embodying the same have been shown in the accompanying drawings in which,—

Fig. 1, is a vertical section of the fuse showing the parts disconnected,

Fig. 2, is a vertical cross-section showing a modification of the plug member,

Fig. 3, is a plan view of Fig. 2, and

Fig. 4, is a side view partly in section and showing a further modification of the plug member.

Referring to the example shown in Fig. 1, 30 my improved magazine plug consists of a screw-threaded plug *a*, a contact disk *b*, a cylindrical part *c*, and an axial bolt *d* connecting the said parts. The plug *a* and the member *c* consists of insulating material. 35 The part *II* is in the form of a cylindrical block or barrel having an axial bore *m* corresponding to and fitting on the member *c*, and the part *III* is in the form of a cap carrying a central internally screw-threaded 40 bushing *e* for being secured to the upper screw-threaded portion of the bolt *d*.

The barrel *II* is formed with longitudinal bores *f* arranged along a circle and adapted to receive the individual fuses *g*. The lower 45 ends of the said individual fuses are secured to metallic plugs *h'* adapted in the assembled position of the device to engage in corresponding notches of the contact plate *b* and thereby to establish electrical connection between the said contact plate, the fuse wire *g*, a cup shaped contact *h''* provided at the upper end of the wire *g*, and a switch arm *i* provided within the cap *III*. The switch arm is connected by the bushing *e* and the

bolt *d* with a central terminal *k* of the magazine fuse.

The switch arm is made with a hole *o* corresponding to a bore *p* made in the cap *III*, so that the explosion caused by the melting of a fuse wire is transmitted to the outer air without injuring the device.

The operation of the device will be understood from the foregoing description of its parts. When the parts have been assembled the contact is made in the manner described above. If now one of the fuses has blown the drum *II* is turned until the next one is in operative position. Arm *i* is arranged inside of the member *III* thereby preventing any possibility of coming in contact with this part. Arm *i* has the usual function of a conductor and of a holding device, whereby the drum *II* is held stationary when a fuse is in operative position. In order that the drum may more easily be turned and to prevent accidental turning of the plug and the cap members *I* and *III* I prefer to construct the drum with a comparatively large diameter.

As I am enabled to construct the upper portion *c* of the plug which supports the barrel with a large diameter the said portion will not be bent by careless manipulation thereof, so that a good contact is insured between the plugs *h'* and the contact plate *b*, and between the cups *h''* and the switch arm *i*. Furthermore, as the individual fuses *g* can not be replaced by unauthorized persons there is no danger that a fuse of improper capacity is inserted. In this respect I prefer to make the construction more reliable by constructing the devices with plugs *c* of different diameters for different capacities of the individual fuses, so that each current intensity corresponds to a plug *c* of a definite diameter.

As the bushing *e* is confined within the cap *III* none of the metallic parts connected with the current supply projects to the outside of the device.

Where it is desired to use a larger number of barrels for different current intensities without materially increasing the dimensions of the members *I* and *III* and to avoid any possibility of inserting wrong fuses, I prefer to construct the member *I* in the manner shown in Figs. 2 and 3, where the plug consists of an inner part *c* and a

prismatic sleeve 7 rotatably mounted thereon. In the manufacture of the device shown in Figs. 2 and 3 the dimensions of the plug and cap members I and III are the same for 5 all the different current intensities, and only the dimension of the prismatic sleeve 7 varies according to the current intensity. The central aperture of the barrel corresponds to the outer configuration of the prismatic 10 sleeve 7.

In the modification shown in Fig. 4 the magazine plug is constructed in such a way that only the operative fuse is connected to the current supply. As shown the disk 51 15 is made of insulating material and a contact piece is embedded therein which is electrically connected with the plug a. The form of the contact piece x corresponds to that of the contact plug h' (shown in Fig. 1). In 20 the assembled position of the device the current flows from the plug a, over the contact piece x, the wire g, the contact piece h'', the switch arm i, the bolt d, and to the terminal k. The individual fuse wires which are in- 25 operative are not connected to the current supply. The member c is of insulating material, preferably porcelain.

The construction shown in Fig. 4 in which only one of the fuses is under electric tension is preferable because thereby the electric arc is avoided when switching in a new fuse wire, which in some cases injures or destroys the wire.

I wish it to be understood that my invention is not limited to the constructions shown 35 in the figures. For example the cooperating contact pieces can be constructed in different ways.

If desired, the insulating disk b¹ is formed with notches y corresponding to the notch 40 made in the contact piece x, so that the pivot member c is not subject to one side pressure.

I claim:

1. A magazine fuse plug, comprising a relatively fixed member, a cap member spaced 45 therefrom and connected therewith, electrical contacts on said members, a rotary member between said contact carrying members, a fuse member removably fixed on said rotary member and rotatable therewith, and 50 fuses within said fuse member located for successively connecting said contacts.

2. A magazine fuse plug, comprising a relatively fixed member, a cap member spaced 55 therefrom and connected therewith, electrical contacts on said members, a rotary member between said contact carrying members, a fuse member removably fixed on said rotary member and rotatable therewith, and 60 fuses within said fuse member located for successively connecting said contacts, the configuration of said rotary member varying according to the capacity of the said fuses.

In testimony whereof I hereunto affix my signature.

JEAN SZYKIER.
